FIG. 1 is a front perspective view of a foldable chair embodying my new design;

FIG. 2 is a side perspective view thereof taken from the left side of FIG. 1;

FIG. 3 is a top plan view thereof;

FIG. 4 is a back elevational view thereof; and

FIG. 5 is a side perspective view thereof taken from the right side of FIG. 1, showing the foldable chair in folded condition.

The design is characterized by the seat of the chair having a wavy configuration across its width in combination with the back rest having a concaved shape with a flared upper edge extending in a rearward direction.

I claim:

The ornamental design for a foldable chair, substantially as shown and described.
